Inventor:

Henry G. Mack

United States Patent Office.

HENRY G. MACK, OF OSWEGO, NEW YORK.

Letters Patent No. 92,982, dated July 27, 1869.

IMPROVED CLOTHES-DRIER.

The Schedule referred to in these Letters Patent and making part of the same

To all whom it may concern:

Be it known that I, HENRY G. MACK, of Oswego, in the county of Oswego, and State of New York, have invented a new and improved Machine for Drying and Airing Clothes, drying fruit, and setting milk; and I do hereby declare that the following is a full and exact description thereof, reference being had to the accompanying drawings, and the letters of reference marked thereon.

The nature of my invention consists more particularly in a new and improved method of attaching several folding frames together, and bracing them in such manner that when in use, they constitute a convenient frame for drying or airing clothes, drying fruit, or setting milk, being sufficiently firm and rigid for that purpose, or when not in use, they may be folded into a small and compact form.

Figure I is a perspective elevation of my improved clothes-frame, fruit and milk-rack.

Figure II is a transverse elevation of the same.

Figure III is a transverse elevation of the same, folded.

Figure IV is a longitudinal elevation of the same, partly folded.

Figure V is a plan of the metallic brace used for bracing the frame transversely, and connecting the sections to each other.

To enable others skilled in the art to make and use my invention, I will proceed to describe its construction and operation.

Letters of like name and kind refer to like parts in each of the figures.

a a a are the standards or uprights, to which the slats *b b* and braces *c c* are attached, by means of screws, the inside or main ones being bolted together

at their upper ends, the bolts forming an axle, upon which they turn in folding, and being attached, by means of hinges, or other connection, to the outer frames at the bottom.

b b are slats or bars of hard wood, having holes through them at suitable places, and of the proper size for the reception of a small screw, which, when driven through them into the standards, will allow the slat to turn easily upon it in folding up.

c c are metallic braces, perforated at *r r r* and *R*, and through *R*, at the point *K*, upon the standard *B*, fastened to the standard *B* by means of a screw, upon which it turns in adjusting the holes *r r r* in *C* to the pins *r' r' r'* in the standards, or in placing it parallel with the standard, as in folding.

d is a brace, working upon a screw-pivot at *t*, and being adjusted to the slat *x*, while in use, or to the slat *z*, for folding.

m m are hinges firmly secured to the bottom of the standards, and upon which the outside frames are made to swing.

Having thus described my invention,

What I claim as new, and desire to secure by Letters Patent, is—

The standards *a*, with side-pieces *b*, hinged at the top and the bottom, in combination with the metallic braces *c*, when constructed and used substantially in the manner and for the purpose described.

In testimony whereof, I have hereunto set my hand, before two subscribing witnesses, this 14th day of April, 1869.

HENRY G. MACK.
